UNITED STATES PATENT OFFICE.

FERDINAND F. METZGER, OF PHILADELPHIA, PENNSYLVANIA, ASSIGNOR TO WILLIAMS, BROWN AND EARLE, INC., OF PHILADELPHIA, PENNSYLVANIA, A CORPORATION OF PENNSYLVANIA.

BLUE-PRINTING MACHINE.

1,022,039.

Specification of Letters Patent.

Patented Apr. 2, 1912.

Application filed March 8, 1911. Serial No. 613,046.

To all whom it may concern:

Be it known that I, FERDINAND F. METZGER, a citizen of the United States, residing at the city of Philadelphia, in the county of 5 Philadelphia and State of Pennsylvania, have invented certain new and useful Improvements in Blue-Printing Machines, of which the following is a specification.

My invention has relation to a machine 10 for printing on sensitized paper in transit from a photograph, drawing or tracing; and in such connection it relates firstly, to the provision of such a machine with a bed so arranged as to be readily shiftable from an 15 inclined vertical position into a substantially horizontal plane. Secondly, to the provision of such a machine with an endless conveyer against which the bed of the machine is in contact in operative position and 20 adapted to be readily slackened, as required, by a manual operation and the endless conveyer mounted on carrier rolls and also provided with a tensioning idler-roll readily shiftable so as to increase or decrease the 25 tension under which the conveyer is maintained in operative relation in contact with said bed. Thirdly, to the provision of such a machine with an endless conveyer having means formed therewith and operating in 30 conjunction with the carrier and idler rolls thereof to maintain true alining movement of the said conveyer in the travel of the same over and around said rolls. Fourthly, to the provision of such a machine with light emitting 35 bodies pivotally supported in front of the machine adjacent to the shiftable bed. Fifthly, to the provision of such a machine with a shiftable bed, light emitting bodies arranged in series and pivotally supported 40 in front of the machine adjacent to said bed and a receptacle arranged to receive a drawing or tracing located beyond the normal position of said light emitting bodies, the constructive arrangement being such that in 45 travel of the endless conveyer a drawing or tracing will be impelled in contact with sensitized paper and along said bed and will be subjected to the influence of said light emitting bodies and the drawing or tracing will 50 then be removed into said receptacle in front of the machine and the printed product will be removed from above the machine and to the rear thereof. Sixthly, to the provision

of such a machine with a framing for receiving and supporting a transparent bed, 55 said framing being held under the tension of spring controlled stud-pins to maintain the said bed free from the influence of heat and cold on both sides of the bed hence to guard against undue cracking or breaking 60 of the bed in use. Seventhly, to the provision of such a machine with a conveyer having a cord or cords located at the respective edges or extending from the body of the conveyer to engage a groove in the 65 surface of the carrier and idler-rolls or to contact with the respective ends of said rolls, to permit thereby of true alining movement in travel of said conveyer with respect to said rolls traveling in contact with the bed 70 of said machine. Eighthly, to the provision of such a machine with a belt conveyer carried by removable carrier rolls and a tensioning idler roll which by its arrangement therewith and contacting with a bed 75 permits of removal of the conveyer from the rear of the machine without disturbing the position of the bed by simply lessening the tension under which the said conveyer is held and removing said rolls. 80 Ninthly, to the provision of such a machine with a bed adapted to be readily shifted from a vertically inclined position so as to assume a substantially horizontal position, thereby to permit of readily cleansing the 85 entire working area of the bed or of replacing the same by another, without disturbing the conveyer and operating parts thereof; and tenthly, to the provision of such a machine with light emitting bodies pivotally 90 supported in front of the machine beyond the shiftable bed and arranged to be manipulated so as to be held in an inoperative position away from the machine.

My invention as above defined, consists of a blue printing machine constructively arranged for operation in substantially the manner hereinafter described and claimed.

In the drawings:—Figure 1, is an end 100 elevational view of a blue printing machine embodying main features of my invention, showing the bed and light emitting bodies in operative position in full lines and in inoperative position in dotted lines. Fig. 2, 105 is a front elevational view of the said ma-

chine with certain of the parts omitted; and Figs. 3 and 4, are respectively, two arrangements of the belt-conveyer, one showing under edge-cords contacting with the ends of 5 a carrier roll and the other showing an under cord projecting from the body of the conveyer so as to enter a groove provided in the carrier roll.

Referring to the drawings, *a*, *a* are side 10 standards of the machine.

*a*¹, is the feed table in front of the machine, as clearly illustrated in Fig. 1.

b, is a framing with feet *b*¹, pivoted to the side-standards *a*. This framing is provided with corner stud-pins *b*², carrying stops *b*³, coiled springs *b*⁴, and nuts *b*⁵.

*b*⁶, is an angle frame with which a glass bed *b*⁷, engages at the edges so as to hold the same under the tension of the spring 20 controlled stud-pins *b*², and in contact with insulating washers *b*¹⁰, of the said pins, thereby to prevent undue cracking or breakage of the glass bed *b*⁷, due to differences in 25 temperature of the air on the respective sides of the said bed, in operative use of the same. The bed *b*⁷, with its framing is locked in its inclined vertical position by threaded swivel-bolts and nuts *b*⁸. These 30 swivel bolts are pivotally connected at *a*⁴, to the upper portion of the side standards *a*, and enter slits *b*⁹, provided in the framing *b*, of the bed *b*⁷, as clearly shown in Fig. 2, so that by loosening the said nuts of the swivel-bolts *b*⁸, they can be thrown 35 backward and the framing of the bed *b*⁷, thereby freed on each side be turned to a substantially horizontal position as shown in dotted outline in Fig. 1.

c, is a series of light emitting bodies 40 connected with a skeleton framing *c*¹, therefor, as shown in Fig. 2, and which framing is pivotally connected with the side standards *a*, of the machine, as clearly shown in Fig. 2. The proper relation of the light emitting bodies with respect to the bed *b*⁷, in 45 operative position, is regulated by stops *a*⁵, provided on the side standards *a* and as shown, struck up therefrom.

d, is a print and drawing or tracing 50 receptacle arranged detachably supported from the framing *b*, of the bed *b*⁷. This receptacle is arranged in front of the machine to enable the operator not only to conveniently receive the tracings but also to be permitted to quickly remove the same for use again and while another tracing or drawing is being printed from in passing through the machine. The said receptacle *d*, is provided with a rear supporting strip 55 *d*¹, as shown in Fig. 1, fitted into the framing of the bed *b*⁷, to support the receptacle *d*, firmly in position.

e, is an endless belt-conveyer mounted on carrier rolls *e*¹ and *e*², and a tensioning idler-

roll *e*³, one of the carrier-rolls, *e*¹, as shown 65 in Fig. 1, being provided with a sprocket-wheel *e*⁴, for a chain *e*⁸, to travel over and a sprocket-wheel *e*¹⁰, of a prime motor *e*⁹, to drive the belt-conveyer *e*. The belt conveyer *e*, is provided on both sides along the 70 under portion with corded edges *e*⁵ and *e*⁶, as shown in Fig. 3, or with only a single cord *e*⁷, arranged centrally in the body of the conveyer as shown in Fig. 4, in the 75 length of the same. In the one instance the corded edges contact with the ends of said rolls, while in the other the centrally extending belt travels in a central groove formed in each of said rolls, as shown in Fig. 4. These arrangements of the belt- 80 conveyer *e*, insure true alining movement of the same over and around the respective carrier rolls *e*¹ and *e*², as well as the tensioning idler roll *e*⁸. The carrier rolls *e*¹ and *e*², are mounted in U-shaped brackets of the 85 side standards *a*, to permit of ready removal, as required, and for purposes as hereinafter explained. The tensioning idler roll *e*⁸, is mounted in U-shaped bearings of bell-cranks *f*, pivoted to the side standards *a*. 90 The opposite end of each bell crank *f*, carries a connecting rod *f*¹, to a foot treadle lever *f*², pivoted to the side standards *a*. The forward portion of the treadle lever *f*², is provided with a vertical rod *f*³, extending through a bracket *a*⁹, of the standards, 95 as clearly shown in Fig. 1. On the vertical rod *f*³, is mounted a spring *f*⁴, and a portion of this rod is threaded and carries a nut *f*⁵, and a washer *f*⁶, to tighten and loosen the 100 said coiled spring, bearing at its respective ends against the bracket *a*⁹, and the washer *f*⁶, whereby through depressing the foot treadle of the lever *f*², the pressure under 105 which the belt-conveyer *e*, is held is lessened to free the conveyer from its taut relation with the bed *b*⁷, to a slackened relation and practically out of contact with the said bed, when from any reason it is desirable such should be slackened to reduce the tension 110 of the conveyer against the bed or the tension of the conveyer against the bed can be increased when the foot treadle is in the position shown in Fig. 1, with the idler-roll *e*⁸, in contact with the belt-conveyer *e*, 115 by simply turning the nut *f*⁵, on the rod *f*³, to compress to a greater degree the spring *f*⁴, between the washer *f*⁶ and bracket *a*⁹, as will be clearly understood from Fig. 1.

It will be observed from Figs. 1 and 2, 120 that as the bed is arranged the entire area is an accessible working surface for sensitized paper receiving by the action of light the print of a drawing or tracing. The tension of the bed is also readily provided for, 125 that is, increased or decreased by means of the four nuts of the stud-pins of the framing *b*, of the bed *b*⁷, to provide against

cracking or breaking of the glass bed owing to differences in temperature of the respective sides of the same. When the light emitting bodies are caused to assume the 5 position shown in dotted outline in Fig. 1, above and beyond the standards *a* of the machine, the framing *c*¹, of said bodies engages rests *a*¹⁰ of the standards *a*, as shown in Fig. 1. Again when the bed is swung 10 into a substantially horizontal plane upon the feed table it can then be thoroughly cleansed, which is highly desirable, if a transparent bed is used to insure better printing from a drawing or tracing upon 15 sensitized paper, or it may be swung into such position to replace a cracked glass of the bed, by another. The provision of a skeleton framing to support singly the series of light emitting bodies therein, enables the 20 entire series of lamps being shifted with facility out of the way of the bed to repair or adjust carbons of the same or to clean the globes of the lamps, quite necessary at stated periods for good practical results in 25 the use of the machine.

Having thus described the nature and objects of my invention, what I claim as new and desire to secure by Letters Patent is:—

1. In a blue printing machine, standards, 30 a normally vertically inclined shiftable bed, means for pivotally supporting the bed to said standards, light emitting bodies, and means, whereby said bodies are pivotally supported from said standards on one side 35 of said bed and are adapted to be shifted over said bed to allow said bed to be shifted into a substantially horizontal position.

2. In a blue printing machine, standards, 40 a normally vertically inclined shiftable bed, a framing for said bed pivotally connected with said standards, means connected with said standards to lock said bed in its vertically inclined shifted position, light emitting bodies, and means whereby said bodies 45 are adapted to be pivotally supported from said standards and to be shifted beyond said bed so as to permit the latter to assume a horizontal position.

3. In a blue printing machine, standards, 50 a normally vertically inclined bed, a framing for said bed and pivotally supporting the same from said standards and arranged so as to be shifted into a horizontal position, means connected with said standards 55 for engaging said framing to lock said bed in its vertically inclined position, light emitting bodies, means connected with said standards whereby said bodies are supported therefrom, and means connected with 60 said standards and adapted to engage the supporting means of said light emitting bodies to limit the position of the same.

4. In a blue printing machine, standards, 65 a normally vertically inclined bed, a fram-

ing for said bed and supporting the bed 65 from said standards so as to permit of the shifting of the bed into a substantially horizontal position, a framing connected with said standards, light emitting bodies arranged in series and carried by said framing, and means connected with said standards and cooperating with said framing to limit position of said bodies with respect to that of said bed.

5. In a blue printing machine, standards, 75 a normally vertically inclined bed, means for pivotally supporting the bed from said standards so as to permit it to be shifted into a substantially horizontal position, a framing connected with said standards, 80 light emitting bodies in series arrangement carried by said framing, and means connected with said standards and adapted to engage said framing to control the operative position of said bodies with respect to 85 that of said bed.

6. In a blue printing machine, standards, 90 a normally vertically inclined bed, means for pivotally supporting the bed from said standards so as to permit it to be shifted 95 into a substantially horizontal position, a framing movably connected with said standards, light emitting bodies arranged in series in and carried by said framing, and means connected with said standards and adapted to engage said framing to regulate the positions of said bodies.

7. In a blue printing machine, standards, 100 a normally vertically inclined bed, means for pivotally supporting the bed from said standards and as so arranged adapted to be shifted into a substantially horizontal position, light emitting bodies arranged in series, means carried by the standards whereby said bodies are pivotally supported from 105 said standards, means adapted to engage the supporting means of said bodies to limit the position of the same with respect to that of said bed, and a receptacle arranged to receive and hold a print and drawing or tracing delivered from the machine.

8. In a blue printing machine, standards, 115 a normally vertically inclined bed, means for pivotally supporting the bed from said standards and as so arranged adapted to be shifted into a substantially horizontal position, a framing pivoted to said standards, light emitting bodies arranged in series in and carried by said framing, means connected with said standards and arranged to 120 engage said framing to limit the position of said bodies in respect to that of said bed, and a receptacle removably arranged in proximity to said bed.

9. In a blue printing machine, standards, 125 a normally vertically inclined bed, means whereby said bed is supported from said standards and so arranged that said bed can

- be shifted into a substantially horizontal position, light emitting bodies, means whereby said bodies are movably supported from said standards, means connected with 5 said standards and adapted to engage the supporting means of said bodies to limit the position of the same with respect to that of said bed, a receptacle arranged to receive and hold drawings or tracings delivered 10 from the machine, and means connected with said receptacle to support the same at a proper angle to said bed.
10. In a blue printing machine, standards, a normally inclined bed, means to 15 movably support the bed from said standards, an endless belt-conveyer held normally in contact with said bed, the latter by means of its supporting means being arranged to be shifted into a substantially horizontal 20 position, said conveyer provided with carrier rolls and a tensioning idler-roll, means to shift the latter roll, light emitting bodies, means whereby said bodies are pivotally supported from said standards and as so ar- 25 ranged adapted to be shifted to either side of said machine, and means connected with said standards and adapted to engage the supporting means of said bodies to limit the position of said bodies.
30. 11. In a blue printing machine, standards, a normally vertically inclined bed, means to pivotally support the bed from said standards, an endless belt-conveyer normally held in contact with said bed, the latter by means of its supporting means being arranged to be shifted into a substantially horizontal position, said conveyer provided with carrier-rolls, brackets in which said rolls are mounted, movable connections, a tensioning idler-roll carried by 35 said connections, and means operatively connected with said connections to vary the tension of said idler-roll in contact with said conveyer.
40. 12. In a blue printing machine, standards, a normally vertically inclined bed, means to movably support the bed from said standards, an endless belt-conveyer held normally in contact with said bed, the latter by 45 means of its supporting means being so ar- ranged as to be shifted into a substantially horizontal position, carrier rolls and a tensioning-roll for said conveyer connected with said standards and said conveyer being 50 provided with edge means to engage the ends of said rolls to maintain said conveyer normally in contact with said bed.
55. 13. In a blue printing machine, standards, a normally vertically inclined bed, means to movably support the bed from said standards, an endless belt conveyer held normally in contact with said bed, the latter by means of its supporting means being ar- 60 ranged to be shifted into a substantially

horizontal position, rolls over which said 65 conveyer is arranged to travel in contact with said bed, said conveyer having means to engage said rolls to maintain said conveyer in its travel in proper relation with said bed in its normal position, light emit- 70 ting bodies, and means whereby said bodies are pivotally supported from said bed and as so arranged adapted to be shifted to either side of said machine.

14. In a blue printing machine, stand- 75 ards, a normally vertically inclined bed, means to movably support the bed from said standards, an endless belt conveyer held normally in contact with said bed, the latter by means of its supporting means being ar- 80 ranged so as to be shifted into a substantially horizontal position, carrier-rolls and a tensioning idler-roll for said conveyer, means to manually shift said idler-roll, and said conveyer having means to bear against 85 said rolls to provide proper relation of the same with said bed.

15. In a blue printing machine, a bed, 90 rolls, open bearings therefor, a belt-conveyer arranged to travel over said rolls nor- 95 mally in contact with said bed, said rolls being supported in said bearings, a tensioning idler-roll similarly supported, and means to shift said idler-roll into and out of contact with said belt-conveyer.

16. In a blue printing machine, standards having U-shaped brackets, a bed, rolls, a belt conveyer arranged to travel over said rolls and normally in contact with said bed, said rolls being detachably supported in 10 said brackets, a tensioning idler-roll similarly supported and a treadle-lever-connection to shift said idler-roll into and out of contact with said belt-conveyer.

17. In a blue printing machine, standards 10. having open bearings, a bed, rolls, a belt-conveyer arranged to travel over said rolls and normally in contact with said bed, said rolls being supported in said bearings, a tensioning idler-roll similarly supported for 110 said belt-conveyer, and a treadle-lever-connection having an adjusting device to vary the tension of said idler-roll in contact with said belt-conveyer.

18. In a blue printing machine, standards 115 having open bearings, a bed, rolls, a belt-conveyer arranged to travel over said rolls and normally in contact with said bed, said rolls being supported in said bearings, a tensioning idler-roll similarly supported for 120 said belt-conveyer, and a treadle-lever-connection having a spring controlled adjust- 125 ing-device to vary the tension of said idler-roll in contact with said belt-conveyer.

19. In a blue printing machine, stand- 125 ards, a normally inclined bed, means to pivotally support the bed from said standards, means connected with said standards to

- lock said bed in its normally operative position, said bed being so arranged as to be shifted into a horizontal position, rolls mounted on said standards, a belt-conveyer 5 passing over said rolls and normally in contact with said bed, one of said rolls adapted to be independently manipulated, means whereby said roll may be adjusted to vary the tension of said conveyer, a series of 10 light emitting bodies, and means whereby said bodies are supported from said standards and arranged so as to be shifted to either side thereof.
20. In a blue printing machine, standards, a normally inclined bed, means to pivotally support the bed from said standards, means on said standards to lock said bed in its operative inclined position, said bed being so arranged as to be shifted into a 20 horizontal position, rolls mounted on said standards, a belt-conveyer passing over said rolls and normally in contact with said bed, one of said rolls being adapted to be independently manipulated, means whereby said 25 roll may be adjusted to vary the tension of said conveyer, light emitting bodies, and means whereby said bodies are supported from said standards and arranged so as to be shifted to either side thereof.
30. 21. In a blue printing machine, standards, a framing pivoted thereto, a transparent bed movably supported in said framing to expose unobstructedly the entire working area of said bed, light emitting 35 bodies, means whereby said bodies are pivotally supported from said standards, and a device connected with said standards and adapted to engage the supporting means for said bodies in one position thereof.
40. 22. In a blue printing machine, standards, a framing movably connected therewith, a transparent bed movably supported in said framing to expose unobstructedly the entire working area of said bed, light 45 emitting bodies, means connected with said standards whereby said bodies are supported on either side of said bed, means connected with said standards and arranged to engage the supporting means of said 50 bodies to limit the position of the same with respect to said bed, and means connected with said standards and arranged to engage the supporting means of said bodies to maintain the same above said standards.
55. 23. In a blue printing machine, standards, a normally vertically inclined bed, means to pivotally support the bed from the standards, means connected with said standards to lock said bed in its vertically inclined operative 60 position, rolls connected with said standards, a belt-conveyer passing over said rolls and normally in contact with said bed, one of said rolls adapted to be manipulated, means whereby said roll may be manipulated to
- vary the tension of said conveyer, light-emitting bodies, means whereby said bodies are pivotally supported from said bed, and a receptacle arranged in proximity to said bed to receive a delivered drawing, tracing, or print. 65
24. In a blue printing machine, standards, a normally vertically inclined bed, means whereby said bed is pivotally supported from said standards and so arranged as to be shifted to assume a substantially horizontal position, light-emitting bodies, means whereby said bodies are pivotally supported from said standards and adapted to be shifted above and beyond said bed, carrier-rolls connected with said standards, 70 an endless belt-conveyer traveling thereover, a tensioning idler-roll for said conveyer, and means connected with said idler-roll and arranged to be manipulated to vary the tension under which said idler-roll is held in contact with said belt-conveyer. 75
25. In a blue printing machine, side standards, a normally vertically inclined bed, means whereby said bed is pivotally supported from said standards and so arranged as to be shifted to assume a substantially horizontal position, light-emitting bodies, means whereby said bodies are pivotally supported from said standards to one side of said bed and arranged so as to be 80 shifted above and beyond said bed, carrier-rolls connected with said standards, an endless belt-conveyer arranged to travel over said carrier-rolls and normally in contact with said bed, a tensioning idler-roll for said conveyer, means connected with said idler-roll to vary the tension under which said idler-roll is held in contact with said belt-conveyer, and a receptacle to receive a drawing, tracing or print delivered from 85 said machine. 90
26. In a blue printing machine, side standards, a normally inclined bed, means to pivotally support the bed from said standards, removable carrier-rolls mounted in 95 said standards, a belt-conveyer carried by said rolls and normally in contact with said bed, a tensioning-roll, means connected with said standards and bed to enable said bed to be shifted to assume a substantially horizontal position, and a framing pivoted to said standards and carrying light emitting bodies suspended therefrom, said bodies being adapted to be shifted out of operative position with respect to said bed. 100
27. In a blue printing machine, side standards, a normally vertically inclined transparent bed, means to pivotally support the bed from said standards and as so arranged adapted to be shifted into a substantially horizontal position, carrier-rolls mounted on said standards, a belt-conveyer carried on said rolls and normally in con- 110 115 120 125

tact with said bed, one of which rolls is arranged to be independently manipulated, means pivoted to said standards, and light-emitting bodies supported from said means
5 and adapted to be shifted to permit of said bed being shifted so as to assume a substantially horizontal position.

In witness whereof, I have hereunto set my signature, in the presence of two subscribing witnesses.
